(Cl. D78—1)

To all whom it may concern:

Be it known that we, Joseph D. McManus and Robert O. Hunt, citizens of the United States of America, residing at Hempfield Township and Greensburg, respectively, in the county of Westmoreland and State of Pennsylvania, have invented a new, original, and ornamental Design for a Valve Handwheel, of which the following is a specification, reference being had to the accompanying drawing, forming part thereof.

Fig. 1 is a top plan view of a valve handwheel embodying our new design, and

Fig. 2 is a side elevation.

We claim:

The ornamental design for a valve handwheel, as shown.

JOSEPH D. McMANUS.
ROBERT O. HUNT.
